ANGUS D. MACLELLAN, OF OWENSBORO, KENTUCKY

MIXING APPARATUS

Application filed August 18, 1926. Serial No. 130,005.

This invention relates to improvements in mixing apparatus, and it consists of the constructions, combinations and arrangements herein described and claimed.

5 An object of the invention is to provide a machine for the purpose described, having such an arrangement of mixing elements as will enable the reduction to a minimum of the time required to mix a given amount of different materials thereby reducing the power consumption, it also being a virtue of the machine that it will continue operation with the least attention of the operator, provide against errors on the part of the operator and 10 permit easy and dustless operation.

Another object of the invention is to provide a novel arrangement for charging and discharging the machine, said means residing in the conveyor housing or tube which is 15 capable of being rotated and has openings which are made to perform the foregoing duties in a manner described later.

Other objects and advantages appear in the following specification, reference being had to the accompanying drawings, in which 20

Figure 1 is a central longitudinal section of the improved apparatus,

Figure 2 is an elevation of the discharge end of the machine,

30 Figure 3 is a cross section of the mixing drum taken on the line 3—3 of Figure 1,

Figure 4 is a vertical section of the sifter bin, taken on the line 4—4 of Figure 1.

In carrying out the invention provision is 35 made of a drum 1, preferably made in cylindrical forms as shown, and herein known as the mixing drum. This drum has tubular hubs 2 in axial alignment, these being carried by flanges, spiders or the like 3, which are 40 suitably secured to the ends of the drum. The hubs are journaled upon two main bearing supports 4, there being a similar pair of main bearing supports 5 and 6 mentioned later. The hubs are held in place by straps 45 7 which complete the bearings.

Special construction within the drum 1 insures a thorough mixing of a plurality of ingredients delivered to the drum and comprises a plurality of so-called hoppers 8 (Figs. 1 and 3) and dividing plates or pans

9. The hoppers are composed of pieces of metal bent along one edge to produce flanges 10 at which they are riveted or otherwise secured at 11 to the ends of the drum 1. The outer extremities of the so-called hoppers 8 are secured to cross pieces 12 at the periphery of the drum. The formation arrived at by the foregoing construction and mode of attachment is that of a three-sided hopper.

55 The so-called pans 9 are suitably secured to rods or bars 13 that extend across the drum 1 parallel to the axis. The hoppers 8 extend in from the end walls of the drum toward the center but do not meet, as shown in Figure 1, thereby leaving a central passageway. The 60 pans 9 are approximately as wide as the passageway, the action being to completely 65 separate a portion of the material from the regular flow and deliver it to the opposite side of the drum into the second or third hopper following.

70 The pans 9 fall short of the center of the drum as indicated at 14. These ends of the pans are open, the sides of the pan being defined by upturned flanges. It is noted that 75 the bottom of each pan is substantially in line with the center of the drum, but the flanges are turned in such manner that diametrically opposite pans face in opposite directions.

80 A conveyor shaft 15, situated axially of the drum 1 extends full length of the apparatus, carrying a small sprocket 16 at one end and a drive pulley 17 on the opposite end. The shaft has a spiral or auger 18 formed 85 thereon, being for the purpose of moving material from one end toward the other of conveyor housing or tube 19 in which the auger works, the necessary driving power being applied at the pulley 17 by any known 90 means. The tube 19 is situated in axial openings in the drum ends and has a lateral opening 20 located within the drum 1, and a pair of lateral openings 21 and 22 located in the neighborhood of the intake 23 and the sifter 95 bin 24 respectively.

100 The conveyor tube 19 may be turned at times. For this purpose it carries a sprocket 25 connected with a sprocket 26 upon a control shaft 27 by means of a chain 28. The

control shaft has a lever 29 by which the turning is done. A pull upon the lever 29 so that it assumes the "down" position will be equivalent to the down position of the opening 20 and the up position of the openings 21 and 22 whereupon the latter receives material and the former discharges the material into the drum. The "up" position of the lever 29 is equivalent to the "up" position of the opening 20 and the "down" position of the openings 21 and 22 (as shown in the drawing) whereupon the former receives the mixed material from the drum in readiness for the discharge thereof at the opposite end of the tube 19.

For the foregoing purposes, especially that of discharging the mixed material, the auger 18 is made sufficiently long that a portion thereof extends from the opening 20 to the discharge casting 30 at which the tube 19 terminates at its left end. The auger and tube perform the two purposes of first conducting the unmixed ingredients to the drum 1, then conducting the mixture from the drum 1 to the point of discharge. The arrangement is such that the drum cannot be charged and discharged at the same time.

The previously mentioned intake 23 is a casting into which the right extremity of the tube 19 extends, and to the right wall of which the auger 18 also extends. This right wall has a bearing 31 in which one end of the conveyor shaft 15 is journaled. The opening 21 in the tube 19 may be brought around in position beneath the intake portion of the casting, an ingredient of one kind being received at this point. The left end of the casting terminates in a flange 32 to which a corresponding flange of the bin 24 is secured in order to insure a good connection. The sifter bin 24 receives an ingredient of another kind. It is divided by a perforated partition 33, formed on part of a circle as shown in Figure 4, so that the brushes 34 of the revolving brush holder 35 may strike across and cause a sifting out of the material.

A shaft 36 which carries the holder 35 has a sprocket 37 (Fig. 1) driven by a chain 38 from a sprocket 39 on a countershaft 40. This countershaft is driven by a chain 41 applied to the sprocket 16 on the conveyor shaft 15 and a sprocket 42 on the countershaft. The countershaft carries a third sprocket 43 which drives a chain 44 and the large sprocket 45 on the drum 1, to which sprocket the chain is applied. Any suitable framework may be employed to support the foregoing parts, the form of framework herein disclosed comprising spaced timbers 46, an upper sill 47 and a plurality of connecting posts 48. The sills support the bearings 49 of the countershaft 40, while the connecting posts serve to support the rest of the structure.

The main bearing supports 4, 5 and 6, men-

tioned before, extend between the connecting posts as shown, it being noted that the intake and discharge castings 23 and 30 are suitably attached and supported to the members 5 and 6. Pieces 50 extending across appropriate ones of the connecting posts 48 provide supports for the sifter bin 24.

The operation may be readily understood. Power is applied to the conveyor shaft 15 in any desired manner, the obvious mode herein disclosed being the application of a driving belt to the fast pulley 17. The turning of the conveyor shaft imparts power to the countershaft 40 so that the mixing drum 1 and the brush holder 35 will revolve simultaneously. Desired relative speeds of the various parts concerned are arrived at by appropriately designing the driving sprocket.

A forward pull upon the lever 29 so that it assumes the "down" position will turn the conveyor tube 19 to such extent that the lateral opening 20 points downwardly in the drum 1 while the openings 21 and 22 point upwardly in the intake casting 23 and the sifter bin 24. Material introduced at these points is moved to the left by the auger 18 and discharged into the drum 1 at the opening 20.

As the drum revolves the ingredients to be mixed will continue falling or sliding down the advancing or raising side of the drum, passing through the hopper formation 8 and the outer wall and end of the drum, causing them to be thrown together and mixed in the central passageway previously mentioned. During this revolution of the drum the pan 9 advances into the material, loads up and carries about one-third of the material up to a point where gravity will cause it to slide off. The sliding action will cause the material to be thrown across the drum to the opposite side into the second or third hopper following.

It is important to observe that the various hoppers 8 and pans or plates 9 are of substantial lengths, extending well over one-half the radial distance of the drum. This arrangement has an important result in the operation of the apparatus for, instead of the pans or plates discharging the portions of material lifted thereby back into the batch at one side of the axial center as they would do were they relatively short, the plates are enabled to discharge said portions across the axial center of the drum into a remote hopper.

The trajectory of the discharged portions of material thus traverses the axial center of the drum, and it is by virtue of this circumstance that said portions are discharged into a remote hopper instead of into an adjacent hopper. The material overflowing the sides of a particular pan or plate does enter an adjacent hopper, but the bulk is propelled to a remote hopper as already emphasized.

5 The action of the so-called hoppers is to mix the ingredients by throwing them together, and the action of the dividing pans is to separate a part of the mixture from the balance and transfer it to one of the hoppers following. Such constant transferring of part of the material from the regular flow to another part of the machine makes a complete separation and transfer, and a perfect mix.

10 After the mixing operation has progressed a suitable length of time the operator moves the lever 29 in the "up" position whereupon the opening 20 in the tube 19 points upward, 15 while the openings 21 and 22 point downward, closing the tube from communication with the casting 23 and 24. Material lifted by the elements within the drum will now be discharged into the opening 20 whereupon 20 the auger 18 moves such material to the left and discharges it into the casting 30 whence it may be conducted to any desired point. The auger and the tube in which it works are thus made to perform a double duty.

25 It is possible, in practice, to operate the apparatus from a floor above and not necessarily from the floor upon which the apparatus is located. In the former instance the intake 23 and bin 24 must have sufficiently 30 long extensions, and some suitable connection must be made for operating the lever 29 to carry out its purpose. The particular showing of four pans 9 and four sets of hoppers 8 must not be taken as a limitation because 35 in the modification for manual use only two of each are shown, while in larger machines more will have to be used.

40 While the construction and arrangement of the improved mixing apparatus is that of a generally preferred form, obviously modifications and changes may be made without departing from the spirit of the invention or the scope of the claims.

I claim:

45 1. Apparatus of the character described comprising a drum, means to revolve the drum, means passing through the drum for conveyance of the material to be acted upon by the apparatus, means carried by the drum and revolving therewith for mixing the material, and means for adjusting the conveying means to either introduce ingredients to the drum in one instance and to conduct the mixture from the drum in another instance.

50 2. Apparatus of the character described comprising a drum, means to revolve the drum, means within the drum to set up a mixing and agitating action, a conveyor tube 55 passing through the drum and having a lateral opening, a continuously revoluble auger situated in the tube, and means to turn the tube so that the opening may discharge ingredients into the drum, fed through the tube by the auger or receive mixed material

from the drum for the discharge of the mixture through the tube by the auger.

3. Apparatus of the character described comprising a drum, elements within the drum for producing a mixing action, means to continuously revolve the drum, a continuously revoluble auger, a tube within which the auger works having a lateral outlet in the drum, and means to turn the tube relatively to the auger bringing the opening either into a lowered returning position or a raised receiving position to either introduce material into the drum by operation of the auger or to carry the mixture away.

4. Apparatus of the character described comprising a drum, means to continuously revolve the drum, elements carried within the drum for producing a mixing action, a plurality of feed points at which various ingredients are discharged, a continuously revolving auger which is common to the drum and to said feed points, a tube containing the auger having openings associated with the drum and with each of said feed points, and means to turn the tube in respect to the auger to either establish communication of said feed points with the drum or to close up said feed points and permit conduction of the mixture from said drum.

5. Apparatus of the character described comprising a drum, means to continuously revolve the drum, elements within the drum revolving therewith to produce a mixing action, a plurality of feed points for supplying ingredients to be mixed, a continuously revolving auger being common to the drum and said feed points, a tube containing the auger having openings located adjacent to said feed points and an opening situated in the drum said openings being diametrically opposite to each other, and means to turn the tube into either of two positions, the first placing said openings in communication with said feed points and directing the drum opening downwardly for the discharge thereinto of ingredients by said auger, the second placing said openings out of communication with said feed points and directing said drum opening upwardly to receive some of the mixture produced therein, said auger moving both the separate ingredients and the mixture in said tube.

6. Apparatus of the character described comprising a drum, elements carried by the drum for producing a mixing action, a plurality of feed points for supplying separate ingredients, a sifter bin situated at one of said points having a perforated partition, a brush movable across said partition, a conveyor tube extending through the drum and past said feed points, there being openings for the drum and said feed points, means to turn the tube to either produce registration or non-registration of certain openings with said feed points, means to revolve the auger for the

5 feeding of ingredients from said points to the drum when the tube is in one position and for the feeding of the mixture in said tube when the tube is in another position, and means for simultaneously revolving the drum and said brush from the auger so that the mixing and sifting actions may be simultaneous with the feeding actions.

10 7. Apparatus of the character described comprising a mixing drum, a plurality of feed points at which the ingredients are supplied, a feeding device which is common to the drum and to the feed points, and means to variously adjust said device to either supply the ingredients to the drum or to convey the mixture from the drum.

15 8. Apparatus of the character described comprising a mixing drum, means to revolve the drum and perform a mixing action, an axial conveyor tube containing an auger for feeding the ingredients to the interior of the drum, bearings for the drum, and tubular hubs carried by the drum resting in said bearings and admitting said conveyor tube.

20 9. Apparatus of the character described comprising a mixing drum, means to revolve the drum and perform the mixing action, feed intake and mixture discharge castings situated exteriorly of the drum, an axial conveyor 25 tube located axially of the drum extending into the castings at the respective ends and containing an auger extending from one casting to the other for moving material, bearings for the drum, and tubular hubs carried by the drum resting in said bearings and fitted around said conveyor tube.

30 10. Apparatus of the character described comprising a supporting framework, feed intake and mixture discharge castings mounted upon the framework each having bearings, a conveyor tube mounted at the ends upon said castings and having an auger journaled in said bearings, means to apply driving power to the auger shaft, a countershaft mounted 35 upon the framework being driven by the auger shaft, a mixing drum, bearings upon the framework for the mixing drum, hubs carried by the mixing drum which are tubular to receive the conveyor tube in a position axially of the drum, means to revolve the mixing drum from the countershaft, and means to turn the conveyor tube to set openings in said tube and located at said intake casting and at the mixing drum in predetermined 40 positions.

45 11. Apparatus of the character described comprising a mixing drum, means extending into the drum for the conveyance of the material to be acted upon, and means for adjusting the conveying means to either introduce the ingredients to the drum in one instance and to conduct the mixture from the drum in another instance.

50 12. Apparatus of the character described comprising a mixing drum, means extending

5 into the drum for the conveyance of the material to be acted upon, means for adjusting the conveying means to either introduce the ingredients to the drum in one instance and to conduct the mixture from the drum in another instance, and means to shift the conveying means into respective positions for either of the foregoing purposes.

70 13. Apparatus of the character described comprising a mixing drum, a conveyor tube introduced into the drum and having an opening communicating with the inside of the drum, an auger working in the tube to handle material, and means to move the tube so that the opening will assume either of two positions, first that ingredients may be discharged from the tube into the drum, and second that the mixture may be discharged from the drum into the tube.

75 14. Apparatus of the character described comprising a mixing drum, a feed auger, means to revolve each independently, a tube incasing the auger and having an opening at the inside of the drum, and means to turn the tube to point the opening either up or down.

80 15. Apparatus of the character described comprising a mixing drum, an auger for charging and discharging the drum, a tube in which the auger works having an opening through which the drum is either charged or discharged and which prevents the drum from being charged at the same time that it is discharging, and means to turn the tube so that the opening points either down or up, permitting the charging and discharging 90 functions of the auger.

95 16. Apparatus of the character described comprising a drum having ends with axial openings, means defining hoppers extending from the periphery substantially to the axial openings for scooping up portions of material and directing and concentrating them toward the peripheral center of the drum, and plates extending from the periphery substantially to the axial openings arranged in even alternation with the hoppers, each plate successively receiving the concentrated portions of material and lifting them for a discharge across the axial center of the drum into a remote hopper, parts of the material lifted by a particular plate overflowing the sides into an adjacent hopper.

105 17. Apparatus of the character described comprising a drum, and plane hoppers and plates arranged in alternation each being longer than one half of the radius of the drum and so circumferentially spaced that the trajectory of material discharged by a particular plate will traverse the axial center of the drum and terminate in a remote 110 hopper.
